UNITED STATES PATENT OFFICE.

SWITS CONDÉ, OF OSWEGO, NEW YORK.

DESIGN FOR A KNIT FABRIC.

SPECIFICATION forming part of Design No. 12,765, dated February 14, 1882.

Application filed December 12, 1881. Term of patent 7 years.

To all whom it may concern:

Be it known that I, SWITS CONDÉ, of Oswego, in the county of Oswego, in the State of New York, have invented new and useful Improvements in Design for Knit Fabric, of which the following, taken in connection with the accompanying drawing, is a full, clear, and exact description.

This design consists in the combination and arrangement of wide mottled stripes and intervening comparatively very narrow plain light stripes, all arranged straight and parallel, as illustrated in the annexed drawing, which represents a piece of knitted fabric embodying my design, and in which *a a* denote the wide mottled stripes, and *b* the narrow plain light stripe.

What I claim is—

The design for knitted fabric, consisting in the combination and arrangement of the wide mottled stripes *a a* and the intermediate comparatively very narrow plain light stripes, *b b*, all arranged straight and parallel, substantially as described, and shown in the annexed drawing.

In testimony whereof I have hereunto signed my name and affixed my seal, in the presence of two attesting witnesses, at Oswego, in the county of Oswego, in the State of New York, this 1st day of November, 1881.

SWITS CONDÉ. [L. S.]

Witnesses:

EDW. MAXWELL,
F. W. TITUS.
